UNITED STATES PATENT OFFICE.

RALPH E. HELLMER, OF PHILADELPHIA, PENNSYLVANIA, ASSIGNOR TO SOUTHWARK FOUNDRY & MACHINE CO., OF PHILADELPHIA, PENNSYLVANIA, A CORPORATION OF PENNSYLVANIA.

CONDENSER.

1,266,260.

Specification of Letters Patent. Patented May 14, 1918.

Application filed December 27, 1915. Serial No. 68,843.

To all whom it may concern:

Be it known that I, RALPH E. HELLMER, a citizen of the United States, residing in Philadelphia, Pennsylvania, have invented 5 a Condensér, of which the following is a specification.

One object of my invention is to provide a surface condenser with means whereby the water of condensation shall be raised to a 10 relatively high temperature, so that it shall not only retain part of the heat of the steam delivered to said condenser but shall be brought more nearly to the temperature at which it may most economically be returned 15 to the boiler;—the invention contemplating a relatively simple, accessible and comparatively inexpensive form of feed water heating attachment for the condenser.

These objects and other advantageous 20 ends I secure as hereinafter set forth, reference being had to the accompanying drawings, in which,

Figure 1 is a plan of a surface condenser equipped with my invention;

25 Fig. 2 is a longitudinal section on the line 2—2, Fig. 1; and

Figs. 3 and 4 are respectively transverse vertical sections on the lines 3—3 and 4—4, Fig. 2.

30 In the above drawings 1 represents a main condenser body in the form of an elongated cylindrical structure having at one end a receiving chamber 2 to which the steam to be condensed is delivered through an inlet 3. The open end of this structure 2 is closed by 35 a head 4 and a tube sheet 5 is confined between it and the adjacent end of the body 1. A second tube sheet 6 is confined between the opposite end of said body and the head 40 7, and two series of tubes 8 and 9 extend between said tube sheets. While all of said tubes open into the hollow of the head 7, those of the series 8 open into the main portion of the inlet casing 2, while the tubes 9 45 open into a condensate chamber 10 formed in said casing by a partition 11. The condenser body 1 is provided with an inlet 13 for cooling water and an outlet 12, there being mounted transversely in said body a 50 baffle 14 whereby such water is compelled to take a more or less tortuous course around the tubes 8 and 9.

Mounted one above the other within the steam receiving casing 2 are a pair of headers 55 15 and 16 provided with tube sheets 17

and 18 between which extend two sets of tubes 19 and 20 both communicating with the header 15. The header 15 is divided by a partition 21 into two chambers 22 and 23, into the first of which open the tubes 19 60 while the second receives the tubes 20. Two pipes 24 and 25 respectively enter the chambers 22 and 23 and a pipe 26 is so connected to the chamber 10 as to drain any liquid collecting therein. 65

The tubes 19 and 20 are so placed in the casing 2 as to lie directly in the path of the exhaust steam passing from the inlet 3 to the tubes 8 and under operating conditions such steam is for the most part condensed 70 in passing through said latter tubes, while the water of condensation together with a small amount of uncondensed steam and non-condensable vapors, after entering the main head 7, passes therefrom into the 75 tubes 9.

In these latter practically all of the remaining steam is condensed and the water of condensation with the non-condensable vapors enter the chamber 10 from which it 80 is drawn through the pipe 26 to a pump. From this latter the water is delivered through the conduit 24 to the chamber 22, and flowing into the tubes 19, passes into the header 16, thence into the tubes 20, chamber 85 23 and out through the conduit 25. Since the tubes 19 and 20 are bathed in or surrounded by the exhaust steam before it has been exposed to the relatively cold surfaces of the condenser, the water of condensation 90 passing through them is heated to a temperature depending on the pressure and volume of the exhaust steam and when discharged through the conduit 25 may pass direct to a feed pump or to further feed water heaters. 95

Obviously the heater comprised by the headers 15 and 16 and their associated parts may be inexpensively installed, and owing to its being placed in the steam receiving chamber 2, is easily accessible upon removal 100 of the cover or head 4. Moreover my device may be applied to a well known form of condenser, such as that illustrated, without material change thereof.

I claim:—

1. The combination of a surface condenser having a body and a steam receiving casing mounted adjacent thereto; headers in said receiving casing; tubes connecting said headers; with means for delivering 110

liquid to and discharging it from a heater comprised by said headers and tubes.

2. The combination of a tubular condenser; a steam receiving casing having an inlet and provided with a partition dividing it into two chambers, of which one communicates with certain of the condenser tubes and the second with others of said tubes; a header mounted on the partition; a series of tubes connected to said header; and a second header also connected to the tubes to provide a liquid heater mounted in the path of steam flowing from the inlet to certain of the tubes of the condenser; with means for supplying liquid to and delivering it from said heater.

3. The combination of a surface condenser

having a condensing chamber and a steam receiving casing adjacent thereto; headers in said casing; tubes extending between said headers within the casing and constituting with the headers a water heater; with means for bracing the headers to the casing independently of the tubes.

4. The combination of a surface condenser containing a body and a steam receiving casing mounted adjacent thereto; a header in the casing provided with two chambers; with means including tubular structures connecting said chambers and extending into the receiving casing in position to be heated by the steam flow therethrough.

RALPH E. HELLMER.
